UNITED STATES PATENT OFFICE.

CHARLES F. MORRIS, OF EARLYSVILLE, VIRGINIA.

PLOW.

Application filed May 14, 1921. Serial No. 469,521.

To all whom it may concern:

Be it known that I, CHARLES F. MORRIS, a citizen of the United States, residing at Earlysville, in the county of Albemarle and State of Virginia, have invented certain new and useful Improvements in Plows, of which the following is a specification, reference being had to the accompanying drawings.

This invention relates to certain improvements in plows and has relation more particularly to a device of this general character of a burster type, and it is an object of the invention to provide a novel and improved implement of this general character which can be employed effectively in connection with virgin soil.

Another object of the invention is to provide a novel improved device of this general character including a ground-working element or member adjustably supported by a beam so that said element or member may be adjusted in accordance with the requirements of practice, and particularly as may be necessitated by the character of the soil.

An additional object of the invention is to provide a novel and improved device of this general character embodying a ground-working element or member having attached thereto a furrow opener.

The invention consists in the details of construction and in the combination and arrangement of the several parts of my improved plow whereby certain important advantages are attained and the device rendered simpler, less expensive and otherwise more convenient and advantageous for use, as will be hereinafter more fully set forth.

The novel features of my invention will hereinafter be definitely claimed.

In order that my invention may be better understood, I will now proceed to describe the same with reference to the accompanying drawings, wherein:

Figure 1 is a view in side elevation of a plow constructed in accordance with an embodiment of my invention, one of the handle members being broken away for clarity in disclosure, a second position of the ground-working element or member being indicated by dotted lines;

Figure 2 is a view in top plan of my improved plow as herein disclosed; and

Figure 3 is a view partly in section and partly in front elevation, illustrating the means for attaching the furrow opener to the ground-working element or member.

As disclosed in the accompanying drawings, B denotes a beam of desired dimensions and which is provided at its rear end portion with an upstanding standard or post 1. Disposed laterally through the upper portion of the standard or post 1 is a tie-rod 2. This rod 2 is secured at its extremities to the handle members 3 disposed on a desired upward and rearward inclination, the forward end portions of the handle members 3 being secured, as at 4, to the opposite side faces of the beam B.

The rear portion of the beam B has disposed therethrough and in the same general direction as the post or standard 1, a slot 5. The opposite sides or longitudinal margins of the opening 5 are defined by the outstanding flanges or webs 6 secured to the upper or top face of the beam B by the bolts 7. The bolts 7 extend entirely through the beam B and also provide means whereby a bearing 8 may be secured to the under surface of the beam B at each side of the opening 5.

Each of the flanges or webs 6 is provided with an arcuate slot 9, concentric to the pivot 10 for the ground-working element or member G. The ground-working member G comprises an elongated and flat body of desired length and which extends above and below the beam B through the opening 5. The central portion of the ground-working element or member G is provided with a series of longitudinally spaced openings 11, through one of which the pivot pin 10 is adapted to be disposed. The pivot pin 10 is also disposed through each of the bearings 8. By providing a series of openings 11, the element or member G may be longitudinally adjusted with respect to the beam B, as the occasions of practice may necessitate. The upper portion of the element or member G is provided with a second series of openings 12 spaced apart similarly to the spacings of the openings 11. A bolt or member 14 is disposed through one of the openings 12 and through the slot 9 of each of the webs 6, said bolt having associated therewith a clamping nut 15. The co-acting bolt 14 and nut 15 provide means whereby the element or member G may be effectively maintained in its different positions about the pivot pin 10.

The lower end portion of the element or member G has its forward marginal portion formed into a cutting edge 16 so that,

in operation, said element or member G operates effectively to break or burst the soil, and particularly virgin soil.

When the member or element G is in the 5 position indicated by full lines in Figure 1, or substantially at right angles to the beam B, the plow is in condition for use with relatively loose soil. When working in close soil or turf, the element or member G is 10 swung about its pivot 10 to bring the cutting edge 16 in a forward and downward incline with respect to the beam B. The cutting edge 16 is also adapted to sever roots or kindred obstructions which may be encountered during a plowing operation. However, should the element or member G come 15 into contact with an unusual obstruction such as a large stone or stump, the operator can readily raise the beam B to permit the 20 element or member G to pass over such obstruction. This is due to the fact that the portion of the beam B, in advance of the member or element G, is of such weight to facilitate the desired raising of the rear portion 25 of the beam and the parts carried thereby.

The lower end portion of the element or member G is provided with a pair of rearwardly directed feet 17, the outer faces of 30 which being curved in the same general direction. The free end portion of each of the feet 17 is bifurcated to provide a kerf 18 through which is directed a holding bolt 19 for a furrow opener or shovel 20. The 35 shovel 20 is held to the outer faces of the feet 17 and is substantially V-shaped in form with the apex portion thereof terminating substantially flush with the lower or free end of the cutting edge 16. As the lower end 40 portion of the member or element G wears, the kerfs 18 in the feet 17 permit the opener or shovel 20 to be adjusted in order to compensate for such wear.

From the foregoing description it is thought to be obvious that a tractor 45 constructed in accordance with my invention is particularly well adapted for use by reason of the convenience and facility with which it may be assembled and operated, and it will also be obvious that my invention is 50 susceptible of some change and modification without departing from the principles and spirit thereof and for this reason I do not wish to be understood as limiting myself to the precise arrangement and formation of 55 the several parts herein shown in carrying out my invention in practice except as hereinafter claimed.

I claim:

1. An implement of the class described 60 comprising a beam provided with an opening therethrough, an elongated member disposed through the opening and extending above and below the beam, means for supporting the member for swinging movement, 65 upstanding webs carried by the beam at opposite sides of the member, said webs being provided with slots, and a clamping medium carried by the member and disposed through the slots of the web for holding the member in different positions. 70

2. An implement of the class described comprising a beam, an elongated member carried thereby and extending therebelow, rearwardly directed feet carried by the member adjacent its lower end, the extremities 75 of the feet being provided with kerfs, a furrow opener abutting said feet, and retaining members for the furrow opener coacting with the furrow opener and the feet of the member, said retaining members being disposed through the kerfs in the feet. 80

In testimony whereof I hereunto affix my signature.

CHARLES F. MORRIS.
